HAIR DRYING APPARATUS

Clyde L. Hunsicker, San Francisco, Calif.

Application April 24, 1939, Serial No. 269,817

3 Claims. (Cl. 183—4)

This invention relates generally to apparatus making use of air currents for drying purposes, and more particularly it relates to apparatus for drying the human hair.

It is a primary object of the invention to provide hair drying apparatus capable of drying a head of hair in a minimum amount of time, and without discomfort to the subject.

A further object of the invention is to provide hair drying apparatus having means for absorbing moisture from the drying air, and having a novel arrangement whereby the moisture absorbing means is automatically re-cycled, as the apparatus is used.

Additional objects of the invention will appear from the following description in which the preferred embodiment of the invention has been set forth in detail in conjunction with the accompanying drawings.

Referring to the drawings:

Fig. 1 is a side elevational view, illustrating hair drying apparatus incorporating the present invention.

Fig. 2 is a cross-sectional detail, taken along the line 2—2 of Fig. 1, and on an enlarged scale.

Fig. 3 is a cross-sectional view, taken along the line 3—3 of Fig. 1.

Fig. 4 is a cross-sectional detail taken along the line 4—4 of Fig. 2.

Fig. 5 is a cross-sectional detail taken along the line 5—5 of Fig. 2.

The present invention makes use of a blower or fan for delivering air upon the head of a subject. The drying action is made more rapid by absorption of moisture from the air, thereby increasing the capacity of the drying air to absorb moisture.

Referring to the drawing, Fig. 1 illustrates a conventional form of blower 10, connected to an air distributor 11. This distributor generally surrounds the head of a subject, and may be helmet shaped or otherwise designed to direct the air upon the head. The air is heated by suitable means such as an electrical heating element 12, carried within the conduit 13 which connects the blower 10 with the distributor 11.

Instead of drawing air into the blower 10 directly from the atmosphere, the intake of the blower is connected to the distributor valve 14, and this valve is in turn connected to the moisture absorbing units 16a and 16b. These moisture absorbing units 16a and 16b may be formed substantially in accordance with the disclosure of my co-pending application Serial No. 231,884, filed Sept. 27, 1938. Briefly the units consist of elongated conduits 11, alongside of which there are suitable electrical heating elements 18a and 18b. Suitable heat insulating material, such as asbestos packing 19, may surround the conduits 11 and the heating elements 18a and 18b, and

5 this packing is in turn enclosed by the outer housing or shell 21. The interior of each conduit 11 is filled with a porous medium 22 capable of absorbing moisture from the atmosphere. As disclosed in my aforesaid co-pending application, Serial No. 231,884, the porous medium preferably consists of fragments of asbestos saturated with calcium chloride, and interspersed in glass wool or a like medium.

10 The distributing valve 14 may vary as to structural details, but in this instance it consists of a body 24 having a cylindrical bore 26. The body 24 is attached directly to one side of the blower 10, so that the intake of the blower is directly connected with the cylindrical bore 26. The valve body is also formed to provide the passages 27a and 27b, which connect with the upper ends of the conduits 11, and with the two vents or ports 28. Extending through the valve body there is a rotatable shaft 29, and this shaft carries the rotatable valve member 31. Segments 32 and 33 forming a part of this valve member, operate in close proximity with the inner periphery of the bore 26, to control flow of air through the passages 27a and 27b. Segment 32 is provided with a recess 34, and in the position of the valve member illustrated in Fig. 4, this recess is in communication with duct 28, thus establishing communication between duct 28 and the passage 27a. Also for the positioning of the parts illustrated in Fig. 4, passage 27b is in communication with the interior of bore 26, and thus with the intake of the blower 10. When the valve member 31 is turned in a counterclockwise direction from the position shown in Fig. 4, to bring segment 32 into a corresponding position with respect to passage 27b, this passage is placed in communication with duct 28, while passage 27a is placed in communication with the intake of blower 10.

40 As shown in Fig. 2 an operating handle 36 is attached to the forward end of shaft 29. Also the forward end of the valve body 24 carries an electrical switching mechanism 37. This switching mechanism may vary as to details of construction, but in the instance illustrated it consists of an insulating disc 38, mounted upon the shaft 29. A contact blade 39 is mounted upon disc 38 and cooperates with two pairs of contacts 41 and 42. These contacts are carried by a suitable insulated mounting 43, which in turn is secured to the end of the valve body 14. The parts just described are shown enclosed within a suitable housing 44. The contacts 41 and 42 are connected in series with the heating elements 18a and 18b, so that each set of contacts, when closed by the blade 39, supplies current to its associated heating element. Connections of this character are indicated in Fig. 1. Current supply conductor 4 is shown connected to one of the terminals 45 for the heating element 18a, while

the other current supply conductor 2 is connected to one of the contacts 42, and also one of the contacts 41. Conductor 3 connects the other one of the contacts 41 with the other one of the terminals 45, and a similar conductor 4 connects the other one of the contacts 42, with one of the terminals 46 for heating element 18b. The other one of the terminals 46 connects with a current supply conductor 1.

For the one operating position of the handle 36 illustrated in Figs. 1 and 4, the contacts 41 are closed and current is supplied to the heating element 18a. This serves to supply heat to the one moisture absorbing unit 16a, while the other unit 16b is placed in communication with the intake of the blower 10. Now assuming that the blower is placed in operation, air is drawn through the moisture absorbing unit 16b and discharged as warm dry air by the blower 10. During such operation of the machine the unit 16a is being heated, and this heat drives out moisture, which may vent in the form of vapor from the lower end of the heat absorbing unit, and also upwardly through the passage 27a, recess 34, and port 28. At the end of this drying cycle, current supply to the entire machine is interrupted. At the commencement of the next drying cycle, the operator turns the handle 36 to its other operating position, and this serves to vent the passage 27b to the atmosphere through recess 34, while passage 27a and unit 16a are placed in communication with the intake of the blower 10. Also contacts 42 are closed to supply current to the heating element 18b. Thus during this next drying cycle air is drawn through the regenerated moisture absorbing unit 16a, while the unit 16b is being heated for the purpose of driving off moisture.

Due to the ability of my machine to absorb moisture from the atmosphere before using the air for drying purposes, the rate of drying a head of hair is greatly accelerated. Because of the use of two moisture absorbing units, in conjunction with the distributing valve 14, and the electrical switching mechanism which is operated in conjunction with the distributing valve, the moisture absorbing units are used in sequence, and as previously pointed out a heat absorbing unit while not in use is being regenerated for the next drying cycle.

I claim:

1. In hair drying apparatus, at least two vertically disposed moisture-absorbing units, each unit comprising a conduit for passage of air and moisture-absorbing materials within the conduit adapted to be dried by application of heat, electrical heating means associated with both said units, and serving to heat said units when energized, an air blower, valve means for controlling communication between said units and said blower, said valve means having at least two openings therein for establishing communication between said blower and said units respectively, said valve means also having passage means formed therein for establishing communication from either of said units to the atmosphere, said valve means having one position in which one of said openings establishes communication between said blower and one of said units and said passage means vents the other of said units to atmosphere, and said valve means having a second

position in which the other of said openings establishes communication between said blower and said unit and said passage means vents said one unit to the atmosphere, electrical switching means for controlling flow of current through said electrical heating elements, whereby either one of said elements can be electrically heated, and a common operating member for operating said valve means and said switching means.

10 2. In hair drying apparatus, at least two vertically disposed moisture-absorbing units, each unit comprising a conduit for passage of air and moisture-absorbing material within the conduit adapted to be dried by application of heat, the lower ends of said units being open to the atmosphere, electrical heating elements associated with both said units, each element being in direct heat conducting relationship with the moisture absorbing material of the associated unit, an air blower, rotary valve means serving to establish communication between the upper ends of said units and said blower, said valve means having two symmetrically disposed openings therein for establishing communication between said blower and said units respectively, said valve means also having a passage formed therein between said openings for establishing communication from either of said units to the atmosphere, said valve means having one position in which one of said openings establishes communication between said blower and one of said units and said passage vents the other of said units to atmosphere and said valve means having a second position in which the other of said openings establishes communication between said blower and said other unit and said passage vents said one unit to the atmosphere, an electrical switching means for controlling flow of current through said electrical heating elements, whereby either one of said units can be electrically heated, and a common operating member for rotating said valve means and for operating said switching means.

3. In hair drying apparatus, at least two vertically disposed moisture-absorbing units, each unit comprising a conduit for passage of air and moisture-absorbing materials within the conduit, an air blower, valve means for controlling communication between said units and said blower, said valve means comprising a casing having respective passages communicating with said units and a pair of opposite apertures open to the atmosphere, said valve means also including a cylindrical valve member communicating at one end with said blower and having symmetrically disposed openings in the side walls thereof and a recess formed in the wall thereof intermediate said openings, said valve means having one position in which one of said openings establishes communication between said blower and the passage to one of said units and said recess connects the other passage with one of said apertures to vent the other of said units to atmosphere, and said valve means having a second position in which the other of said openings establishes communication between said blower and the passage to the said other unit and said recess connects the said one passage to the other of said apertures to vent said one unit to the atmosphere, and an operating member for said valve means.

CLYDE L. HUNSICKER.
